UNITED STATES PATENT OFFICE

140,253

DESIGN FOR AN EYEGLASS FRAME

Louis Jacobson, New York, N. Y.

Application May 23, 1944, Serial No. 113,723

Term of patent 7 years

(Cl. D57—1)

To all whom it may concern:

Be it known that I, Louis Jacobson, a citizen of the United States and a resident of the city, county, and State of New York, have invented a new, original, and ornamental Design for an Eyeglass Frame, of which the following is a specification, reference being had to the accompanying drawing forming part thereof, wherein Fig. 1 is a front view of an eyeglass frame showing my new design; Fig. 2 is a top plan view thereof.

My design for an eyeglass frame having the essential features shown in full lines on the drawing is characterized by the angularity of the nose rest opening, as shown most clearly in Fig. 1.

I claim:

The ornamental design for an eyeglass frame, substantially as shown and described.

LOUIS JACOBSON.
